UNITED STATES PATENT OFFICE.

HENRY G. THOMPSON, OF NEW HAVEN, CONNECTICUT, ASSIGNOR TO THE NEW HAVEN NOVELTY MACHINE COMPANY, OF SAME PLACE.

DESIGN FOR AN ANGLE-COUPLING.

SPECIFICATION forming part of Design No. 33,224, dated September 18, 1900.

Application filed August 17, 1900. Serial No. 27,215. Term of patent 14 years.

To all whom it may concern

Be it known that I, HENRY G. THOMPSON, a citizen of the United States, residing at New Haven, county of New Haven, and State of Connecticut, have invented and produced a new, useful, and original Design for an Angle-Coupling, of which the following is a specification, reference being had to the accompanying drawings, forming a part thereof.

10 Figure 1 shows in side elevation an angle-coupling, illustrating my design; and Fig. 2 is a view looking at one end thereof.

As shown in the accompanying drawings, the leading feature of my design for an angle-coupling consists in an elongated tubular body curved longitudinally between its ends, one end having a series of peripheral grooves and the other end being provided with a peripherally-grooved circular enlargement or 15 flange having a tapering projection extended from its outer face. The elongated tubular

body f is curved longitudinally between its ends, as at f^x , Fig. 1, and at one end the body has a series of peripheral grooves f' , the other end of the body having a circular enlargement or flange f^2 , peripherally grooved, as at f^3 , a tapering projection f^1 extending from the outer face of the enlargement in axial alignment with the adjacent portion of the body. 25

Having fully described my design, what I claim as new, and desire to secure by Letters Patent, is—

The design for an angle-coupling, substantially as herein shown and described. 30

In testimony whereof I have signed my name to this specification in the presence of two subscribing witnesses.

HENRY G. THOMPSON.

Witnesses:

H. GRANT THOMPSON,
GEORGE E. HAIGHT.
